UNITED STATES PATENT OFFICE.

HOWARD L. INGERSOLL, OF POUND RIDGE, NEW YORK.

DRAFT CONNECTION.

Application filed February 13, 1925. Serial No. 8,860.

This invention relates to draft mechanism. One object of the invention is to provide a safe, strong, durable and efficient coupler and yoke combination including a connection between the coupler and yoke which will permit proper pivotal or radial action.

Another object is to provide a coupler and yoke with improved cooperating means whereby said coupler and yoke may be readily connected and disconnected.

Another object is to provide a coupler and yoke combination in which the various parts cooperate in an improved manner to meet all of the requirements under service conditions.

These and other objects are accomplished by means of the arrangement disclosed by the accompanying sheet of drawings, in which

20 Figure 1 is a side elevation of a coupler and yoke embodying my invention, only the rear portion of the coupler being shown, and the usual cushioning unit mounted between the arms of the yoke also not being shown;

Figure 2 is a top plan view of the arrangement shown in Figure 1;

Figure 3 is a fragmentary detail top plan view of the coupler butt;

30 Figure 4 is a top plan view of the coupler butt and yoke showing the coupler butt in a position ninety degrees from its normal position for connecting or disconnecting the coupler butt and yoke;

Figure 5 is a sectional view taken in the plane of line 5—5 of Figure 1;

Figure 6 is a fragmentary sectional view taken in the plane of line 6—6 of Figure 2;

Figure 7 is a sectional view taken in the plane of line 7—7 of Figure 1, and

40 Figure 8 is a detailed side elevation of the coupler butt showing the latter with a vertical keyhole extending therethrough to make the coupler interchangeable for use with a key-slotted yoke.

The various novel features of the invention will be apparent from the following description and drawings, and will be particularly pointed out in the appended claims.

Referring to the figures of the drawings, it will be noted that my invention is illustrated in connection with draft mechanism including a yoke having upper and lower arms 10 and 11 respectively which are integrally connected at their rear ends by a

strap portion 12. A filler block 13, formed either separately or integrally, is located between the yoke arms 10 and 11 at the rear of the yoke adjacent the strap portion 12. 60 The forward ends of the yoke arms 10 and 11 are provided with inwardly-extending lugs 14 which are tapered and undercut, as shown at 15, for a purpose to be described hereinafter. These lugs 14, which extend 65 vertically toward each other and, as shown, are preferably completely frustro-conical, form trunnions upon which the butt 16 of a coupler 17 pivots for the usual radial action required under actual service conditions. In this connection it will be seen that the rear of the coupler butt is provided with outwardly or oppositely extending lugs 18, which take the form of a U-shaped or semi-circular wall at the upper and lower 70 sides of the coupler butt. Said semi-circular lugs 18 embrace one hundred and eighty degrees of the yoke arm lugs 14 and conform in curvature with respect to said yoke arm lugs 14 to readily permit radial action of the 75 coupler with respect to the yoke. The semi-circular, oppositely-extending lugs 18 on the coupler butt 16 also are tapered and undercut, as shown at 19, to cooperate with the tapered undercut lugs 14 to prevent spreading 80 of the yoke arms under draft conditions.

The rear end of the coupler butt is spherically convex, as shown at 20, and cooperates with a spherically concave surface 21 formed in the front of a bridging wall 22 which is 90 integrally formed with and acts as a spacer between the arms 10 and 11 of the yoke. By thus making the cooperating lugs 14 and 18 of the yoke arms and coupler butt correspond in curvature and taper, and by making the spherically convex surface 20 on the coupler butt correspond to the spherically concave surface 21 on the bridging piece 22, the coupler is permitted to pivot or have the necessary radial action in accordance with 95 the requirements of all service conditions.

The hemispherical butt of the coupler will be in contact, or nearly so, with the hemispherical surface of the bridging piece 22 at all times. They will be in direct contact with each other under buffing conditions and will be but slightly out of engagement with each other under draft conditions. The clearance between the lugs 14 and 18 and between the hemispherical surfaces is 100 merely sufficient to permit the coupler to act radially and to permit the coupler and 105 110

yoke to be connected and disconnected with respect to each other. With respect to connecting and disconnecting the coupler and yoke, they are moved into a position at right angles with respect to each other, as shown in Figure 4 of the drawings. In said figure it will be noted that the lugs 18 of the coupler butt have been moved into engagement with the lugs 14 on the yoke arms. 5 If it is desired to complete the connecting movement between the coupler and yoke, the former is moved through an angle of ninety degrees so that the yoke and coupler are in alignment. When in such position 10 said coupler and yoke are locked with respect to each other in so far as operation thereof is concerned. If it is desired to disconnect said coupler and yoke, the same may be accomplished by removing the 15 coupler from its position of alignment with the yoke, as shown in Figure 2, to the right angle position as shown in Figure 4, whereupon the coupler may be moved in a perpendicular line with respect to the yoke for 20 moving the lugs 18 and 14 out of operative relationship. In this manner the coupler and yoke may be readily connected and disconnected.

By means of this arrangement a cast steel 30 yoke may be used. Furthermore, by means of this arrangement it is not necessary to spring the yoke arms for connecting and disconnecting the coupler with respect thereto, as disclosed in my Patent No. 35 1,447,178, granted March 6, 1923. The lugs and their bearing areas may be made as large as desirable, as there is ample space to accommodate relatively large lugs and it will be noted that the adjacent upper and 40 lower surfaces on the coupler and yoke are normally parallel, thereby increasing the bearing area between the members. It will be appreciated that a front follower 23 will be used directly to the rear of the bridging 45 piece 22.

If desired, the coupler butt may be provided with a key slot 24, as shown in Figure 8, to make the coupler interchangeable for use with a key-slotted yoke. The key slot 50 24 could be shown in Figure 1, as well as in Figure 8, but it is omitted in Figure 1 for the sake of clearness.

It is my intention to cover all modifications of the invention falling within the 55 spirit and scope of the following claims:

I claim:

1. In draft mechanism, the combination of a coupler having a butt with tapered undercut lugs, and a yoke having cooperating completely frusto-conical undercut lugs for 60 forming a pivotal connection between said coupler and yoke and preventing spread of parts of the latter.

2. In draft mechanism, the combination of 65 a coupler having a butt with outwardly ex-

tending tapered undercut lugs, and a yoke having arms with inwardly extending frusto-conical undercut lugs, said undercut lugs on the coupler embracing those on the yoke to form a pivotal draft connection between 70 said coupler and yoke and preventing spreading of the arms of the latter.

3. In draft mechanism, the combination of a coupler having a butt with outwardly extending tapered undercut lugs, and a yoke 75 having arms with inwardly extending tapered undercut lugs, said tapered undercut lugs cooperating on three sides to form a direct pivotal draft connection between said coupler and yoke and preventing spreading 80 of the arms of the latter.

4. In draft mechanism, the combination of a coupler having a butt with lugs and a rear curved surface, a yoke having arms with lugs of less width than and cooperating with 85 said lugs on said coupler butt to form a pivotal draft connection between said coupler and yoke, said yoke having a cross member connecting said yoke arms acting as a spacer and having a curved surface cooperating with the curved surface of said coupler.

5. In draft mechanism, the combination of a coupler having a butt with lugs and a rear spherically curved surface, a yoke having arms with frusto-conical lugs cooperating 95 with said lugs on said coupler butt to form a pivotal draft connection between said coupler and yoke, said yoke having a cross member connecting said yoke arms acting as a spacer and having a spherically curved 100 surface cooperating with the curved surface of said coupler.

6. In draft mechanism, the combination of a coupler having a butt with lugs, a yoke having arms with lugs circular in cross section 105 cooperating with said other lugs to form a pivotal draft connection between said coupler and yoke, said yoke having integrally formed therewith a spacer connecting said yoke arms rearwardly of said coupler.

7. In draft mechanism, the combination of a coupler having a butt with tapered undercut lugs and a rear curved surface, a yoke having arms with tapered undercut lugs completely circular in section 115 cooperating with said other lugs on said coupler butt to form a pivotal draft connection between said coupler butt and yoke, said yoke having a cross member connecting said yoke arms acting as a spacer and having a curved surface 120 cooperating with the curved surface of said coupler butt.

8. In draft mechanism, the combination of a coupler having a butt with tapered undercut lugs and a rear spherically curved surface, a yoke having arms with tapered undercut lugs of less width than and cooperating 125 with said other lugs on said coupler butt to form a pivotal draft connection between said coupler butt and yoke, said yoke having a 130

cross member connecting said yoke arms acting as a spacer and having a spherically curved surface cooperating with the spherically curved surface of said coupler butt.

5. In draft mechanism, the combination of a coupler having a butt, a yoke, said coupler butt and yoke having cooperating lugs engaging on three sides and forming a pivotal

draft connection between said coupler butt and yoke, said coupler butt and yoke being 10 disengageable only by relative movement from normal position approximately ninety degrees.

Signed at New York, New York, this 9th day of February, 1925.

HOWARD L. INGERSOLL.
